CARTRIDGE MAGAZINE

Jacob Sofinowski III, Baldwin, and Nicholas J. LaCosta,
Phoenix, Md.

Filed Dec. 3, 1975, Ser. No. 637,347

Term of patent 14 years

Int. Cl. D22—05

U.S. Cl. D22—7

FIG. 1

FIG. 1 is a perspective view of a cartridge magazine according to the invention, with the normally bottom end facing upwardly.

FIG. 2 is a rear end elevation view of the cartridge magazine of FIG. 1.

FIG. 3 is a right side elevation view of the cartridge magazine of FIG. 1.

FIG. 4 is a bottom plan view of the cartridge magazine.

FIG. 5 is a top plan view of the cartridge magazine.

FIG. 6 is a front elevation view of the cartridge magazine.

FIG. 7 is a left side elevation view of the cartridge magazine.

We claim:

The ornamental design for a cartridge magazine, substantially as shown.
